US0D1099052S

(12) **United States Design Patent** (10) **Patent No.:** **US D1,099,052 S**
(45) **Date of Patent:** **** Oct. 21, 2025**

(54) **CONTROL PANEL MODULE**

(71) Applicant: **Danfoss Power Electronics A/S**,
Gråsten (DK)

(72) Inventor: **Michael Sørensen**, Gråsten (DK)

(73) Assignee: **DANFOSS POWER ELECTRONICS**
A/S, Gråsten (DK)

(**) Term: **15 Years**

(21) Appl. No.: **29/872,502**

(22) Filed: **Mar. 14, 2023**

Related U.S. Application Data

(62) Division of application No. 29/738,728, filed on Jun.
19, 2020, now Pat. No. Des. 1,010,589.

(57) **CLAIM**

The ornamental design for a control panel module substantially as shown and described.

DESCRIPTION

FIG. 1 is a front, right side and top perspective view of the control panel module comprising a new, original and ornamental design;

FIG. 2 is a front view thereof;

FIG. 3 is a back view thereof;

FIG. 4 is a top view thereof;

FIG. 5 is a bottom view thereof;

FIG. 6 is a right view thereof; and,

FIG. 7 is a left view thereof.

The broken lines illustrate portions of the control panel module and form no part of the claimed design.

1 Claim, 6 Drawing Sheets
